UNITED STATES PATENT OFFICE.

LE ROY MALTBY, OF CEDAR RAPIDS, IOWA.

RUBBER OVERSOLE.

1,119,185.

Specification of Letters Patent.

Patented Dec. 1, 1914.

Application filed February 4, 1914. Serial No. 816,550.

To all whom it may concern:

Be it known that I, LE ROY MALTBY, a citizen of the United States, residing at Cedar Rapids, in the county of Linn and State of Iowa, have invented certain new and useful Improvements in Rubber Oversoles, of which the following is a specification, reference being had to the accompanying drawings.

10 This invention relates to certain improvements in oversoles and the object of the invention is to provide a device of this general character having novel and improved means whereby the same may be conveniently and 15 effectually engaged with the sole of a shoe.

Still another object of the invention resides in providing a device which is simple and durable in construction, inexpensive to manufacture and one which will be very 20 efficient in use.

With these and other objects in view, the invention consists in the novel features of construction, combination and arrangement of parts as will be hereinafter referred to 25 and more particularly pointed out in the specification and claim.

In the accompanying drawing forming a part of this application, Figure 1 is a side elevation of an oversole constructed in accordance with my invention. Fig. 2 is a bottom plan view thereof. Fig. 3 is a fragmentary transverse section as seen on line 3—3, Fig. 1, and Fig. 4 is a similar view as seen on line 4—4, Fig. 1.

30 In describing my invention, I shall refer to the drawing in which similar reference characters designate corresponding parts throughout the several views and in which 1 indicates an oversole formed of rubber of the usual character provided for rubber oversoles, the same being provided along the edges thereof with an upstanding and inwardly inclined sole engaging flange 2. This flange may be of any desired height 35 to project above the sole and engage the lower portion of the upper, whereby to aid in the retention of said sole in place when applied to the sole of a shoe. As stated, this oversole 1 is formed of the usual rubber 40 composition provided for use in connection with overshoes and the shank 3 of this sole is formed for the greater portion thereof of live rubber, indicated as 4. This sole, with the shank thereon is of such a length as to 45 permit the free edge of the shank portion to

be spaced from the heel seat when the complete oversole is applied to use on a shoe.

The flange 2, formed on the edge of the sole 1, terminates substantially at the junction of the shank 3 with the sole proper and I have provided an improved means in connection with the shank for the securing of the latter in place on the shank of the shoe, to which the same is to be applied. To this end, blocks 5 formed of textile material are 60 inserted in the live rubber 4, adjacent the rear edge thereof and along the side edges of the shank and mounted in these blocks 5, are the ends of a pair of upwardly curved hook members 6 which are designed for engagement with the shank of the sole of a shoe. When the oversole proper has been applied to the sole of a shoe and the hooks 5 suitably engaged with the shank of the sole of said shoe, this device will be securely 70 held in place thereon.

The device is so sized as to require stretching both longitudinally and laterally in the application thereof to use. Thus, in applying the device after the sole of a shoe has 80 been properly fitted in this oversole, so that the flange 2 projects over and above the sole of the shoe proper, it is necessary to stretch the device from the shank portion thereof rearwardly or longitudinally, such 85 stretching being made possible in view of the live rubber portion 4 thereof. After stretching the same longitudinally, it is necessary to stretch the same laterally also, in order to permit the hooks 5 to be engaged 90 with the narrowest portion of the shank of the sole. In view of these conditions, it will be seen that after the application of the device to the sole, in a manner as described, the portion 4 tending to return to 95 its initial or normal position, will draw the hooks 6 forwardly and inwardly and cause the same to bind tightly against the shank of the sole of the shoe, thus securely retaining the complete oversole in position on the 100 shoe. This will admit of the use of this device for rough walking or for dancing purposes and, in either instance, the use thereof will positively prevent the wearer 105 from slipping as would be true under ordinary conditions.

From the foregoing it will be seen that I have provided a simple, inexpensive and efficient means for carrying out the objects of the invention and while I have particu- 110

larly described the elements best adapted to perform the functions set forth, it is obvious that various changes in form, proportion and in the minor details of construction may 5 be resorted to without departing from the spirit or sacrificing any of the principles of the invention.

Having thus described this invention, what I claim is:—

- 10 An over appliance for shoes comprising a half sole, a flange formed thereon adapted to grip the edges of the sole of the shoe, a laterally and longitudinally yieldable shank

provided for said sole, the longitudinal edges of said shank having recesses formed 15 therein and arranged in transverse alignment with each other, blocks of textile material secured in the recesses and hook members secured in the textile material adapted to engage the shank of a shoe sole. 20

In testimony whereof I hereunto affix my signature in the presence of two witnesses.

LE ROY MALTBY.
